UNITED STATES PATENT OFFICE.

DANIEL WOODHEAD, OF CHICAGO, ILLINOIS, ASSIGNOR TO CENTRAL ELECTRIC COMPANY, OF CHICAGO, ILLINOIS, A CORPORATION OF ILLINOIS.

CAR CONSTRUCTION.

1,071,851.

Specification of Letters Patent

Patented Sept. 2, 1913.

Application filed March 19, 1913. Serial No. 755,293.

To all whom it may concern:

Be it known that I, DANIEL WOODHEAD, a citizen of the United States of America, and resident of Chicago, Cook county, Illinois, 5 have invented a certain new and useful Improvement in Car Construction, of which the following is a specification.

My invention relates to an improvement in car construction, and more particularly 10 to the feature of providing a car construction with a concealed lighting arrangement whereby the lighting fixtures and their appurtenances are hidden from the view of the passengers.

15 My invention is particularly adaptable for railway cars in which electric fixtures are employed for lighting purpose, although, in its broader aspects, my invention might be employed with fixtures of other types.

20 Heretofore various systems for indirect lighting have been employed, but with my construction, however, not only is the method of indirect lighting employed—that is, having the car illuminated by the rays 25 of light reflected from the ceiling of the car—but, furthermore, the lighting fixtures are entirely concealed from view, and in this manner not only is a very efficient form of car lighting obtained, but the appearance of 30 the car is greatly improved, as the objectionable lighting features which usually adorn the upper portion of the car are entirely removed.

35 My invention will be more clearly understood by having reference to the accompanying drawings, in which I have illustrated one embodiment of my invention.

In the drawings—Figure 1 is a cross sectional view of a portion of a car embodying 40 the features of my invention. Fig. 2 is a sectional view taken on the line 2—2 in Fig. 1, looking in the direction of the arrows. Fig. 3 is a sectional view taken on the line 45 3—3 in Fig. 1, looking in the direction of the arrows.

Referring to the drawings, I have illustrated a portion of a car of the standard type, consisting of a roof section 5, carried by the angle plate 6 secured to the sash 7, 50 to the lower end of which sash is connected the deck sill plate 8 carrying the deck 9. The false carline plate 10 is secured to the deck sill plate, while secured to the angle iron 6 is a false ceiling 11, all of which 55 construction is of the well known type,

and it is not thought necessary to describe the same more in detail.

The features of my invention consists in securing to the lower portion of the false carline plate 10 a molding 12, which molding projects inward about four inches and then extends upwardly, being shaped into an artistic design. This molding is preferably made of thin sheet steel and extends the entire length of the car, being supported 60 in various places intermediate of its ends, by means of suitable braces 13.

Located in the space formed between the lower part of the molding 12 and the plate 10, I provide a block of insulating material, 70 through which pass suitable conduits. I have shown three conduits, although it will be understood that any suitable number can be employed, through which conduits pass either electric wires or signaling cords. 1 75 employ one of these conduits for the electric light circuit, and along the upper surface of the insulating block I mount suitable sockets which carry the electric light bulbs for illuminating the car. These lights can 80 be distributed in any desired manner in order to provide sufficient illumination. In order to provide a suitable reflector for these lights, I provide a curved reflector 14 secured at its outer end to the molding 12 85 and at its inner end to the sash 7. This reflector passes immediately beneath the bulb of the light and above the socket, and in this manner I provide a more efficient reflecting surface as this surface is not broken 90 by the lamp socket. These reflectors are preferably made of sheet steel, and to facilitate handling are made in sections of about four feet long. The brace bars 13 are provided for supporting the molding. 95

In order to prevent dirt or dust accumulating around the lights in the reflector 14, I provide a glass cover 15 hinged at one side to the sash, whereby this cover can be raised in order to reach the lighting fixtures. 100

It will thus be seen that I have devised a very efficient and improved form of lighting arrangement for car construction, and one in which an evenly distributed light is obtained due to the employment of the indirect lighting, the rays of light being first deflected toward the false ceiling 11, and thence deflected downward to the car below. Furthermore, it will be seen that all the lighting fixtures are entirely concealed, and 110

this is accomplished by merely having the molding along the side of the car extending into the car a few inches. This leaves a free space in the upper portion of the car, thus giving better ventilation, and likewise greatly improving the appearance of the car.

While I have thus described one particular form of my invention, it will be readily understood that various changes and modifications can be made without departing from the scope of my invention.

What I claim as my invention is:

1. In car construction, a deck sill, a deck sill plate secured thereto, a false ceiling, a series of lights mounted adjacent to said deck sill plate and carried thereby, means for directing the rays of light against said false ceiling, whereby said rays are deflected to the lower portion of said car, and means for concealing said lights from view from the lower portion of said car.

2. In car construction, a roof section, a false ceiling carried thereby, a deck plate, a deck sill plate secured thereto, a molding projecting inward from said deck sill plate, and a series of lights located between said molding and said deck sill plate, said molding concealing said lights from all points below the same.

3. In car construction, a ceiling; a deck, a deck sill plate secured thereto, a molding adjacent said deck sill plate and projecting inward therefrom, a series of lights located between said deck sill plate and said molding, whereby said molding conceals said lights from all points below the same, and a reflector arranged below said lights to there-

by reflect the light against the ceiling of the car from which it is deflected to the car below.

4. In car construction, a deck sill, a deck sill plate secured thereto, a molding carried by said deck sill plate and projecting inward from the same, a series of conduits between said molding and deck sill plate, and a series of lights mounted within said molding, whereby they are concealed from view from all points below said molding.

5. In car construction, a roof portion, a false ceiling carried thereby; a deck, a deck sill plate secured thereto, a molding carried by said deck sill plate and projecting inward therefrom, a series of electric lights each including a bulb and a socket located between said plate and said molding, and a curved reflector mounted immediately below said bulb and above said socket for reflecting the light against said false ceiling, said molding acting to conceal said lights from all points below the same.

6. In car construction, a roof, a false ceiling carried thereby, a deck sill plate, a lamp carried thereby, a reflector for reflecting the rays from said lamp against said false ceiling, and a molding carried by said plate for concealing said lamp from view at all points below the same.

Signed by me at Chicago, Illinois, this 15th day of March 1913.

DANIEL WOODHEAD.
